ORNAMENTAL DOLL

Stefany Salomon, née Herzog, Berlin, Germany
 assignor of one-half to Sidi Dukas, née Reinemann, Berlin-Grunewald, Germany

Application October 4, 1938, Serial No. 233,271

4 Claims. (Cl. 46—162)

This invention relates to an ornamental doll, which can be produced in many different forms, and the peculiarity of which resides more particularly in a very convenient and simple manner to form the inner structure and the body of the doll.

Thus, for example, an essential feature of the ornamental doll according to the invention resides in the provision of an inner structure composed merely of four open wire loops bent in hairpin fashion, three of which, having the ends of their limbs set together at an angle to one another and being connected together at said ends by a wire binding, form the legs of the doll, whilst the fourth wire loop engaging at its bent end with the connected ends of the first three loops constitutes the inner reinforcement or the body of the doll and extends with its free ends into the hollow interior of and thus carries the head of the doll.

Another feature of the doll according to the invention is to provide the two arms of the doll of a wire having a wrapping of tissue paper, which wire, after the same has been bent to represent a pair of arms, and upon the formation of the body of the doll by a repeated winding of a strip of tissue paper about said fourth wire loop, is included within this wrapping of tissue paper, whereby the arms are secured to the body.

Still another feature of the present invention is to secure the head of the doll to the body in similar fashion by including the breast portion of the head within the wrapping of said tissue paper upon formation of the body of the doll.

A doll designed according to the invention provides in particular the possibility of making up the garment parts for the doll for the greater part from articles of daily use, such as pocket-handkerchiefs, dusters, or the like, which can be secured to the body of the doll by means of pins, wire, tape or cord, so that for the purpose of use they may be again readily removed.

The invention is illustrated by way of example in the accompanying drawings, in which

Fig. 1 shows different parts of which the inner structure of the doll may consist.

Fig. 2 shows the aforesaid parts loosely connected together.

Fig. 3 illustrates the wrapped body of the doll.

Figs. 4 and 5 are front views illustrating diagrammatically two respective dolls in dressed condition, whilst

Fig. 4a is a rear view of the upper portion of the doll according to Fig. 4, the outer garment being removed.

Fig. 6 is a rear view of the upper portion of the doll according to Fig. 5.

The dolls in the embodiments illustrated each possess an inner structure comprising four wire loops 1, 2, 3, 4 bent in hairpin or substantially U-shaped fashion. The three wire means or loops 1, 2 and 3, disposed at an angle to one another as shown in Fig. 1, are connected together at their upper free ends by means of a wire 6 wound about the same and then constitute the legs of the doll. The loop or wire member 4 is fitted at its bent end 5 about the connected ends of the loops 1, 2 and 3 held together by said wire 6, as shown in Fig. 2, and extends upwardly into the hollow interior of the head 7, which is conveniently produced from papier-mâché.

The two arms of the doll are formed by a single substantially U-shaped wire piece 8, about which, as shown in Fig. 2, there is wound a flexible strip, preferably of tissue paper 9.

A strip of tissue paper 10 is wound about the three legs 1, 2 and 3 until a desired thickness of said wound paper has been attained, and a further strip of paper 11, which in this case, if desired, may be wider than the other strips, is wound about the loop 4 for the purpose of producing the torso. Upon the production of the torso or body 12 by the wrapping of the strip of paper 11 about the U-shaped wire member 4 the paper 11 is preferably also wrapped over the suitably bent wire piece 8 forming the arms, as shown in Fig. 3, the wire piece 8 having previously been wrapped in the strip of paper 9. The lower neck portion of the head 7 is preferably also included in the wrapping 11, causing the head to be secured to the torso.

A doll produced in this manner and as shown in Fig. 3 can then be dressed with garments or garment parts of paper or textile material as desired, in which connection the strips of paper 9, 10 and 11 forming holding means for said material are preferably selected in a color to match the color of the garment material.

The doll illustrated by way of example in Fig. 4 possesses sleeves 14 composed of paper with similar cuffs 15, a jacket 16 also composed of paper, and two trouser-leg portions 17—17 covering the legs 1 and 3, which trouser-legs may conveniently consist of pocket-handkerchiefs. These handkerchiefs 17 are suitably folded and at the upper ends are secured by pins 18 to the torso 12, which consists for the greater part of paper, whilst at the lower ends they are passed about the legs 1 and 3 and are pinned together at 19. One of the trouser-leg portions formed by handkerchiefs 17

(Fig. 4) has been left open at the lower end thereof to show partly the inner structure.

In the embodiment according to Figs. 4, 4a the arms 8, in contradistinction to the arms 9 of Fig. 3, have not been included within the wrapping formed by the strip 11, but are placed together with the sleeves 14 against the back of the torso 12 and are secured thereto by means of a wire 20, as shown in Fig. 4a.

10 In the doll illustrated in Fig. 5, the torso 12 is unclothed, whilst the sleeves 21 consist of paper. In this embodiment the arms 8 with said sleeves 21 are included in the wrapping 11 about the torso 12, as shown in Fig. 6. The lower garment parts 15 comprise a petticoat 23 composed of paper and two pocket-handkerchiefs 24—24, which can be folded as desired, and can be secured together with the petticoat 23 to the lower end of the torso 12 by means of a tape or cord 25, in which case 20 the correct position of the garment parts on the torso 12 can be ensured by means of pins (not shown).

In the embodiment according to Fig. 4 the lower ends of the legs forming loops 1, 2, 3 are bent in the form of feet. In Fig. 5, the legs forming wire means or loops are so disposed in spaced apart relation to one another, and particularly, the rearward leg 2 is bent in such fashion with respect to the remaining legs, that the 30 doll will safely stand in upright position.

What I claim as new and desire to secure by Letters Patent is:

1. In an ornamental doll, a structure forming a skeleton, said structure comprising U-shaped wire means in spaced apart relation and having the free ends of the arms thereof connected to each other, a U-shaped wire member extending from said connected ends and adapted for receiving a hollow doll head thereon, flexible strip means wound about said wire means and said member for forming holding means, and at least a foldable fabric article of every day use forming a garment for said doll, said article being detachably secured to said holding means, said spaced apart U-shaped wire means being adapted to sustain said doll in an upright position.

2. In an ornamental doll, a structure forming a skeleton, said structure comprising three U-shaped wires in spaced apart relation and having the free ends of the arms thereof connected to each other, a U-shaped wire member extending 5 from said connected ends and adapted for receiving a hollow doll head thereon, a strip of tissue paper wound about said wires and said member to form holding means, and foldable fabric articles of every day use forming garment 10 parts for said doll, said articles being detachably secured to said holding means, said spaced apart U-shaped wires being adapted to sustain said doll in an upright position.

3. In an ornamental doll, a structure forming 15 a skeleton, said structure comprising a plurality of U-shaped wires in spaced apart relation forming means for sustaining said doll, the free ends of the arms of said U-shaped wires being connected to each other, an upwardly extending wire 20 member attached to said connected ends and adapted for receiving a hollow doll head on its free end, flexible strip means wound about said wires and said member for forming holding means, and foldable fabric articles of every day 25 use forming garment parts for said doll, said articles being detachably pinned to said holding means.

4. In an ornamental doll, a structure forming 30 a skeleton, said structure comprising a plurality of U-shaped wires in spaced apart relation forming means for sustaining said doll, the free ends of the arms of said U-shaped wires being connected to each other, an upwardly extending wire 35 member attached to said connected ends and adapted for receiving a hollow doll head on its free end, a piece of wire forming the arms of said doll connected to a predetermined point of said wire member, flexible strip means wound about said wires, said wire piece and said member 40 for forming holding means, and foldable fabric articles of every day use forming garment parts for said doll, said articles being detachably pinned to said holding means.

45 STEFANY SALOMON, NÉE HERZOG.
